ELECTRIC VALVE CONVERTING SYSTEM

Richard Tröger, Berlin-Zehlendorf-Mitte, and
Otto Renner, Berlin-Glienicke-Nordbahn, Germany, assignors to General Electric Company,
a corporation of New York

Application June 21, 1939, Serial No. 280,336
In Germany July 29, 1938

8 Claims. (Cl. 175—363)

Our invention relates to electric valve converting systems and particularly to such systems wherein a plurality of serially connected electric discharge valves are utilized.

For very high voltage installations where electric valve converting systems are used, it has sometimes been found desirable to operate a plurality of electric valves in series whereby at least two important advantages are obtained. In the first place, each individual discharge valve need not be designed to withstand the full voltage of the system, and in the second place, much greater reliability of operation is obtained for in the present state of development of commercial electric discharge valves one cannot be sure that the individual valves will never fail. However, by using a number of electric discharge valves in series the probability of failure of the system can be greatly reduced. Furthermore, even though any one electric discharge valve should fail the strain on the remaining serially connected valves would be increased only by a small amount and the probability of failure of the remaining valves would be very remote. When such valves are connected in series and employed in high voltage installations, there exists the danger that the voltages, and especially the inverse voltages, will not be uniformly distributed among the various valves and a large proportion of the inverse voltage may appear across one of the valves causing it to flash over. If, however, some means were provided for causing the various valves to assume equal proportions of the voltages impressed upon them, this difficulty would be eliminated. It has been suggested in such arrangements that the secondary winding of the electric valve converting apparatus transformer be subdivided into a number of individual windings and that each of the serially connected electric discharge valves be joined to one of these subdivided windings so that the total voltage is uniformly graded and positively distributed among the various serially connected discharge valves. However, since electric discharge valves sometimes fail or arc back even at normal voltages impressed upon them, it is necessary to provide some means to maintain the increase in current which occurs when one of the serially connected valves arcs back within safe limits. Specially designed transformers have been used which afford a high reactance in case of abnormal current conditions but these transformers are both difficult and expensive to construct, and furthermore can only be operated within a very definite range. Accordingly, we provide an arrangement wherein a normal trans-

former may be used in connection with the electric valve converting apparatus and yet wherein arc back currents are kept within safe limits.

It is an object of our invention to overcome the disadvantages above noted in connection with electric valve converting apparatus employing serially connected discharge valves.

It is another object of our invention to provide a new and improved electric valve converting system.

It is a further object of our invention to provide a new and improved electric valve converting system of the type wherein a plurality of serially connected electric discharge valves are used.

In accordance with the illustrated embodiment of our invention, we provide an arrangement for limiting the arc back current in an electric valve converting apparatus for transmitting energy between a polyphase alternating current circuit and a direct current circuit through a plurality of groups of serially connected electric discharge valves, one group of serially connected valves for each phase of the alternating current supply circuit. Uniform distribution of voltage among the serially connected valves is positively obtained by means of a subdivided secondary transformer winding having one of the subdivisions connected between each of the serially connected valves. A plurality of inductive windings are provided for limiting the arc back current in any of the valves which windings offer a very high impedance to arc back currents and yet offer a very limited or negligible impedance to the normal flow of current through the electric valve converting apparatus.

The novel features which we believe to be characteristic of our invention are set forth with particularity in the appended claims. Our invention itself, however, will best be understood by reference to the following description taken in connection with the accompanying drawings in which Fig. 1 is a diagrammatic representation of an electric valve converting apparatus employing a plurality of of serially connected valves to which our invention has been applied; Fig. 2 is a modification of the embodiment illustrated in Fig. 1, and Fig. 3 is a modification of the arrangement illustrated in Fig. 2.

Referring now to Fig. 1 of the drawings, we have illustrated therein an electric valve converting apparatus for transmitting energy between an alternating current circuit 13 and a direct current circuit 11. Although our invention is applicable to any of the electric valve converting systems well known in the art in which a

plurality of serially connected electric discharge valves are utilized whether converting from alternating to direct current, or vice versa, for simplicity in disclosure and explanation we have illustrated an arrangement wherein three-phase alternating current is converted into direct current.

As illustrated, a transformer 12 has its three-phase Y-connected primary phase windings 13, 13' and 13'' energized from the alternating current source 10. These windings are wound on a suitable three phase core symbolically shown as 14. On each of the legs of core 14 of transformer 12 are wound the secondary phase windings which are subdivided into a number of steps for each phase. The subdivisions of the secondary winding associated with primary phase winding 13 are designated by the numerals 15, 16, 17 and 18, while correspondingly those associated with primary phase winding 13' are designated as 15', 16', 17' and 18' and those associated with primary phase winding 13'' are designated by numerals 15'', 16'', 17'' and 18''. A plurality of electric discharge valves 19, 20, 21 and 22 are connected between each step of the subdivided secondary windings 15, 16, 17 and 18, respectively, while the electric discharge valves 19', 20', 21' and 22', 15'', 20'', 21'' and 22'' are connected, respectively, between each step of the subdivided secondary windings 15', 16', 17', 18', 15'', 16'', 17'' and 18''. Electric discharge valves 19 to 22'' may be any of the electric discharge valves well known to those skilled in the art, although our invention is particularly applicable for use with the type of valves wherein a plurality of electrodes are mounted within an envelope containing an ionized medium. Accordingly, we have shown each of the electric discharge valves 19 to 22'', respectively, as comprising an anode 23, a cathode 24, and a control electrode or grid 25. The cathodes of the electric discharge valves 22, 22' and 22'' are connected through a suitable smoothing reactor 26 to one side of the direct current circuit 11, while the other side of the direct current circuit 11 is connected to one terminal of each of the subdivided secondary windings 15, 15' and 15''. In order to maintain the arc back current within safe limits in case one of the electric discharge valves should fail we provide inductive windings 27, 28, 29, 30-30a, 27', 28', 29', 30'-30a', 27'', 28'', 29'', 30''-30a'', connected in series with the cathodes of each of the valves 19 to 22'', respectively. Each of the inductive windings 27 to 29'' comprises a plurality of coils 31 and 32 reversely wound upon a suitable core 33. A normal flow of current through the coils 31 and 32 in series will produce zero resultant ampere turns and hence there will be zero resultant flux in core 33. Thus inductive windings 27 to 29'' will offer a very low impedance to normal current flow through the serially connected electric discharge valves 19 to 22, 19' to 22' and 19'' to 22''. In connection with the last electric discharge valves in the series connected groups for example, discharge valve 22, there is provided a coil 31 wound on core 33 which is inductively related, by means of windings 34 and 34a connected in a series circuit, with reversely wound coil 32 thus operating in the same manner as inductive windings 27, 28, etc. Similarly inductive windings 30'-30a' and 30''-30a'' comprise reversely wound coils 31 and 32 inductively related by means of windings 34'-34a' and 34''-34a'', respectively.

The operation of the electric valve converting

system may briefly be described as follows: An alternating potential derived from the polyphase source 10 is applied to the primary phase windings 13, 13' and 13'' of transformer 12 and correspondingly to the subdivided secondary phases 15, 16, 17, 18, 15', 16', 17', 18', 15'', 16'', 17'' and 18''. The phase embodying the particular group of serially connected discharge valves 15 to 22, 15' to 22' or 15'' to 22'' upon the anodes of which the highest positive potential relative to the cathode is impressed at any instant will be conductive as is well understood by those skilled in the art. Let us assume, for example, that current is flowing through electric discharge valves 19, 20, 21 and 22, through smoothing reactor 26 to the direct current circuit 11 and returns from the other side of the direct current circuit 11 to the anode 23 of electric discharge valve 19 through coil 32 and subdivision 15 of the secondary winding of transformer 12. It will be observed that this current flows through the reversely wound coils 31 and 32 of each of the inductive windings 27, 28, 29 and 30-30a connected in series with the respective discharge valves 19, 20, 21 and 22. Since the resultant or net ampere turns of inductive windings 27 to 30-30a are zero the impedance offered to the current flowing through these windings during normal operation is negligible. When the positive potential applied to the next group of serially connected valves 19', 20', 21', 22' becomes equal to or higher than the potential applied to the serially connected valves 19, 20, 21, 22 which have just been conducting current, commutation of current between the groups of valves will occur and valves 19', 20', 21' and 22' begin to conduct current. If now an arc back should occur, for example, in electric discharge valve 19 current will tend to flow through coil 31 of inductive winding 27, through coil 31 of inductive winding 27 and through electric discharge valve 19 in the reverse direction. Since a corresponding current does not flow through coils 32 of inductive windings 27 and 27' their ampere turns are no longer neutralized and the net resultant flux induced in the cores 33 is no longer zero. It follows, therefore, that a high impedance is offered by coils 31 of inductive windings 27 and 27' to the arc back current thus maintaining it within safe limits. The coils 31 of inductive windings 27 and 27' thus become effective chokes to limit the arc back current and yet afford little or no impedance to the normal operating current. It will of course be understood that inductive windings 27, 28, 29 and 30-30a instead of being wound on four individual cores symbolically shown as 33, may all be wound on one single phase core. Also, it would be possible that each of the inductive windings 27, 27' and 27'' be wound on a three-phase core instead of three single phase cores 33 as illustrated in Fig. 1, since the mid-points of inductive windings 27, 27' and 27'' are all interconnected by means of conductor 35. Hence, a plurality of three-phase cores embodying the inductive windings 27, 27', 27''; 28, 28', 28''; 29, 29', 29''; and 30-30a, 30'-30a', 30''-30a'' may be connected between the corresponding discharge valves of all of the phases. The arrangement may be still further simplified by placing all the inductive windings 27, 27', 27'', 28 . . . 30''-30a'' on a common three-phase core as will be understood by those skilled in the art.

From the operation just described of the apparatus illustrated in Fig. 1 when an arc back

occurs in discharge valve 19, it will be observed that due to the inductive coupling of coils 31 and 32 a voltage may be induced in coil 32 of both windings 27 and 27' when arc back current flows in coils 31 and 31' of the inductive windings. This voltage induced in coils 32 of inductive windings 27 and 27' will cause a voltage to be impressed on electric discharge valves 20 and 20' without affecting the voltage impressed on the remaining electric discharge valves 21, 22 and 21', 22' of the respective serially connected groups. This additional voltage may cause an arc back in electric discharge valve 20, for example, whereas if this voltage due to arc back current were divided equally among the remaining valves no additional arc back would occur. Hence it would be desirable to have a uniform distribution of this voltage among the remaining discharge valves so that the probability of arc back in the remaining electric discharge valves becomes more remote. This result is obtained by the arrangements disclosed in Figs. 2 and 3.

In Fig. 2, the corresponding circuit arrangements are characterized by the same reference numerals as in Fig. 1. For simplicity in disclosure, however, only three serially connected electric discharge paths for each phase have been shown as contrasted with the four illustrated in Fig. 1. Alternating current from alternating current supply circuit 10 is converted to direct current supplied to direct current circuit 11 by means of the electric valve converting apparatus embodying transformer 12 and a plurality of serially connected discharge valves 19, 20, 21; 19', 20', 21'; and 19'', 20'', 21'', respectively for each phase of the polyphase alternating supply circuit 10 similar to the arrangement disclosed in Fig. 1. In order to maintain the arc back current within safe limits in case one of the electric valves should fail we provide inductive windings comprising transformers 36, 36', 36'', 37, 37', 37'' and 38, 38', 38'', one winding of which is connected in series with each of the cathodes 24 of electric discharge valves 19 to 21'', respectively. The other windings of transformers 36, 37 and 38 are connected in series in a closed circuit 39. In a similar manner the other windings of transformers 36', 37' and 38' are connected in series in a closed circuit 40 and the other windings of transformers 36'', 37'' and 38'' are connected in series in a closed circuit 41. During the normal operation of the electric valve converting apparatus illustrated in Fig. 2 the plurality of transformers 36 to 38'' afford little or no impedance to the normal currents flowing through the serially connected electric discharge valves since the impedance afforded by these transformers is the same as that of a transformer with a short circuited secondary winding. If, however, an arc back occurs in one of the electric discharge paths, for example in electric discharge valve 19, then a reverse current will tend to flow through the winding of transformer 36 connected in series with the cathode 24 of electric discharge valve 19. Assuming for example, that at the instant an arc back occurs in valve 19 electric discharge valves 19', 20' and 21' are conductive then the reverse current flowing through the winding of transformer 36 in series with cathode 24 of electric discharge valve 19 will induce a current in the other winding of transformer 36 which is connected in closed circuit 39 in series with corresponding windings of transformers 37 and 38. However, since no current is flowing at this time through electric 75

discharge valves 20 and 21, the windings of transformers 37 and 38 which are in series with these valves are effectively open circuited and hence these transformers afford a very high impedance to any current flowing in circuit 39 and furthermore transformer 36 affords a very high impedance to the arc back current thus maintaining it within safe limits. The advantage of this arrangement over that disclosed in Fig. 1 resides in the fact that whenever an arc back occurs the current which is caused to flow in closed circuits 39, 40 or 41, depending upon the particular valve which arcs back, will cause the additional potential created by virtue of the arc back current to be divided equally among the remaining valves in the particular serially connected group of valves containing the valve which has failed, and hence an equal distribution of the voltage will be obtained as contrasted with Fig. 1 wherein all the voltage will appear on the next adjacent series connected discharge valve.

Although in Fig. 2 we have illustrated the inductive windings comprising transformers 36 to 38'' as connected in series with the cathodes of electric discharge valves 19 to 21'', it will be understood that these inductive windings could equally well be connected in series with the anodes of the respective discharge valves. This latter arrangement has the advantage that electric discharge valves comprising a plurality of anodes may then be used instead of a single electric discharge valve for each serially connected discharge path. Accordingly, in Fig. 3 we have shown inductive windings comprising transformers 36, 36', 36'', 37, 37', 37'', 38, 38', 38'', connected in series with the respective anodes of the various discharge paths. Also, instead of separate discharge valves 19, 19', and 19'' we have shown a single discharge valve 42 comprising a plurality of anodes 23 and a single cathode 24. Likewise electric discharge valves 20, 20' and 20'' of Fig. 2 have been shown as a single discharge valve 43 in Fig. 3 and discharge valves 21, 21', 21'' have been shown as a single discharge valve 44 in Fig. 3. The operation of the electric valve converting apparatus illustrated in Fig. 3 is of course identical with that described in connection with Fig. 2 and will be well understood by those skilled in the art.

While we have shown and described particular embodiments of our invention as applied to an electric valve converting apparatus, it is to be understood that this is merely illustrative as one of a number of electric valve converting or translating apparatus to which our invention may be applied. It will, of course, be obvious to those skilled in the art that changes and modifications may be made without departing from our invention and we, therefore, aim in the appended claims to cover all such changes and modifications as fall within the true spirit and scope of our invention.

What we claim as new and desire to secure by Letters Patent of the United States is:

1. Apparatus for transmitting energy between direct and alternating current circuits comprising a plurality of electric discharge valves connected in series relation, means for impressing an electromotive force upon said valves, electric translating apparatus connected in parallel with each of said discharge valves, and a plurality of inductive windings, connected between successive ones and in series relation with each of said electric discharge valves for limiting the arc back current due to the failure of any valve.

2. In combination, a polyphase alternating current circuit, a direct current circuit, means for transmitting energy between said circuits comprising a plurality of electric discharge valves arranged in groups according to the number of phases of said polyphase alternating current circuit, the valves of each group being connected in series relation, means comprising a plurality of inductive windings effectively connected in series with the valves of each group and offering a low impedance to load current flowing in a normally conducting group of valves while offering a large impedance to current flow resulting from any of the valves in the other groups becoming conductive in a reverse direction.

3. In an electric valve converting system, the combination of a plurality of serially connected electric discharge valves, means for impressing an electromotive force upon said valves, and means including an inductive winding comprising a pair of reversely wound coils connected in series with said valves for limiting the arc back current due to the failure of any valve.

4. Apparatus for transmitting energy between direct and alternating current circuits comprising a plurality of electric discharge valves connected in series relation, means for impressing an electromotive force upon said valves, and a plurality of transformers each having one of their windings connected in the anode circuit of one of said serially connected valves while the other windings are connected in series in a closed circuit with all the corresponding windings of said transformers associated with those valves connected in series relation.

5. In combination, a polyphase alternating current circuit, a direct current circuit, means for transmitting energy between said circuits comprising a plurality of electric discharge valves arranged in groups according to the number of phases of said polyphase alternating current circuit, the valves of each group being connected in series relation, means comprising a plurality of transformers one winding of each transformer being connected in series with the cathode of each of said electric discharge valves while the other winding of said transformer is connected in series with the corresponding windings of the remaining transformers associated with one of said groups of electric discharge valves for limiting the current when any one of said plurality of valves becomes conductive in the reverse direction.

6. In combination, a polyphase alternating current circuit, a direct current circuit, means for transmitting energy between said circuits comprising a plurality of electric discharge valves ar-

ranged in groups according to the number of phases of said polyphase alternating current circuit, the valves of each group being connected in series relation, means comprising a plurality of 5 transformers one winding of each transformer being connected in series with the anode of each of said electric discharge valves while the other winding of said transformer is connected in series with the corresponding windings of the remaining 10 transformers associated with one of said groups of electric discharge valves for limiting the current when any of said plurality of valves becomes conductive in the reverse direction.

7. In combination, a polyphase alternating current circuit, a direct current circuit, means for transmitting energy between said circuits comprising a plurality of electric discharge valves and a main transformer, said plurality of electric discharge valves adapted to be serially connected in groups according to the number of phases of said polyphase alternating current circuit, said main transformer having a primary winding connected to said polyphase alternating current circuit and a secondary winding provided 15 with a plurality of subdivisions according to the number of electric discharge valves arranged in each of said groups, the valves of each group being connected in series relation with the subdivisions of the secondary winding of said transformer in order to positively insure equal distribution of potential on all the electric discharge valves connected in series, and means comprising a plurality of inductive windings for limiting the current when any of said plurality 20 of valves becomes conductive in the reverse direction.

8. In combination, a polyphase alternating current circuit, a direct current circuit, means for transmitting energy between said circuits comprising a plurality of electric discharge valves arranged in groups according to the number of phases of said polyphase alternating current circuit, the valves of each group being connected in series relation, means for limiting the arc 25 back current due to the failure of any valve including an inductive winding comprising a pair of reversely wound coils connected in series with the valves of each group, said reversely wound coils having a common terminal, and means for 30 completing an electrical circuit between the common terminal of the reversely wound coils associated with one of said groups of valves with the common terminal of the reversely wound coils associated with each of the other groups of 35 valves.
